(57) CLAIM

The ornamental design for a portable alarm as shown and described.

DESCRIPTION

FIG. 1 is a front, left and bottom perspective view of a portable alarm.

FIG. 2 is a front view of the portable alarm of FIG. 1.

FIG. 3 is a rear view of the portable alarm of FIG. 1.

FIG. 4 is a right side view of the portable alarm of FIG. 1.

FIG. 5 is a left side view of the portable alarm of FIG. 1.

FIG. 6 is a top view of the portable alarm of FIG. 1; and,

FIG. 7 is a bottom view of the portable alarm of FIG. 1. The broken lines in the drawing figures illustrate features that form no part of the claimed design.
